DESIGN FOR A DECK OF PLAYING CARDS

Fredric J. Threlfall, Philadelphia, Pa.

Application May 11, 1938, Serial No. 77,125

Term of patent 3½ years

To all whom it may concern:

Be it known that I, Fredric J. Threlfall, a citizen of the United States, residing at Philadelphia, in the county of Philadelphia and State of Pennsylvania, have invented a new, original, and ornamental Design for a Deck of Playing Cards, of which the following is a specification, reference being had to the accompanying drawings, forming a part thereof.

Referring to the drawings, Fig. 1 is a face view of the king of spades;

Fig. 2 is a face view of the queen of clubs;

Fig. 3 is a face view of the queen of diamonds;

Fig. 4 is a face view of the jack of hearts;

Fig. 5 is a face view of the ace of diamonds;

Fig. 6 is a face view of the three of clubs;
Fig. 7 is a face view of the six of spades;
Fig. 8 is a face view of the nine of hearts; and
Fig. 9 is a face view of the ten of diamonds.

Figs. 1 to 5 inclusive show all of the picture designs of a complete deck of playing cards, while Figs. 6 to 9 inclusive fully represent the designs of the remaining pip cards which complete the deck. The design of the backs of the cards composing the deck is conventional.

I claim:

The ornamental design for a deck of playing cards, substantially as shown and described.

FREDRIC J. THRELFALL.
